Primary Examiner — Cynthia Underwood(74) *Attorney, Agent, or Firm* — Nixon & Peabody LLP(57) **CLAIM**

The ornamental design for cup, as shown and described.

DESCRIPTION

FIG. 1 is a perspective view of a cup.

FIG. 2 is a first side view of the cup.

FIG. 3 is a second side view of the cup, which is adjacent to the first side view of FIG. 2.

FIG. 4 is a top plan view of the cup; and,

FIG. 5 is a bottom plan view of the cup.

The portions of the drawings shown in broken lines represent environmental structure and form no part of the claimed design.
